BINDER

Lawrence J. Thoel, Chicago, Ill., assignor to
Isidore Spinner, Chicago, Ill.

Application April 11, 1941, Serial No. 388,138

5 Claims. (Cl. 129—1)

This invention relates to binders in general and, more particularly, to mechanical binders of the type adapted to be inserted through aligned perforations in a stack of pages for binding them together.

The binder of the present invention is of the type shown in the patent to Douvry, No. 1,970,285, issued August 14, 1934, and comprises a back from which extend a plurality of fingers that are curled into loops, the free ends of the fingers overlapping the back. When binders of the above mentioned type are made for large or heavy books or stacks of pages they must, of course, be made comparatively stiff. When so made it frequently happens that a tooth or series of teeth are forced along the back beyond their normal position and a distance such as to exceed the elastic limit of the material. This permanently deforms the individual fingers or loops that have been thus forced beyond their normal position, and destroys the aesthetic appearance of the binder and may also interfere with the turning of the bound pages. It is one of the objects of the present invention to provide a binder which will overcome this difficulty by preventing inward movement of the teeth or fingers in the loop beyond their normal position. This is accomplished, in one preferred embodiment of the present invention, by forming a plurality of down struck tabs in the back, which tabs form abutments for limiting the extent of peripheral sliding of the fingers in the loop.

It is a further object of the present invention to provide a binder of the above mentioned character with means for preventing the accidental withdrawal of the ends of the fingers from the loop, that is, for preventing the accidental opening of the loop, while at the same time permitting the loop to be opened when it is desired to do so. In accordance with this embodiment of the invention the rings or fingers are provided with projections adjacent their end, which projections enter into slots in the back. By this arrangement a direct outward pull on the fingers is ineffective to withdraw the fingers from the loop. The fingers may, however, be withdrawn from the loop by first pressing them away from the back to withdraw the finger tab from the slot in the back and then uncurling the finger or fingers. It is a still further object of the present invention to provide such a binder wherein the tab on the finger which limits accidental retraction of the finger cooperates with the very slot that is formed by the tab in the back for limiting the inward movement of the finger in the loop.

It is a still further object of the present invention to provide a binder of the above mentioned character wherein the fingers of the loop extend through slots in the back to prevent movement of the fingers longitudinally of the back while at the same time avoiding any appreciable projections of the back inwardly or outwardly of the binder.

It is a still further object of the present invention to provide a binder of the above mentioned character wherein the fingers are held against inward movement in the loop and yet are smooth along all of their edges and surfaces and free of outer projections from any of the surfaces, thus facilitating insertion of the smooth fingers into or removal from aligned perforations in a stack of sheets to be bound together.

While the structure of the present invention is particularly applicable to binders, it is not limited to binders. Individual rings or groups of rings may be provided to act as binders for securing any other parts together. For instance, individual rings may be used as key rings, napkin rings, or the like. Also, individual rings or groups of rings may be used as supports for hanging curtains or the like.

The attainment of the above and further objects of the present invention will be apparent from the following specification taken in conjunction with the accompanying drawings forming a part thereof.

In the drawings:

Figure 1 is a plan view of a blank from which a binder of the present invention is to be made;

35 Figure 2 is a sectional view taken along the line 2—2 of Figure 1 and looking in the direction of the arrows;

Figure 3 is a transverse sectional view through a binder inserted through a stack of pages;

40 Figure 4 is a diagrammatic view illustrating the manner of inserting the binder of Figure 3 into the stack of pages;

Figure 5 is a fragmentary perspective view of the end of a book bound by the binder of Figure 3;

45 Figure 6 is a perspective view of a strip for forming an individual binder ring embodying the present invention;

Figure 7 is a perspective view of a ring formed from the strip of Figure 6;

50 Figure 8 is an end view of a blank for forming another embodiment of the present invention;

Figure 9 is a plan view of the blank of Figure 8;

Figure 10 is a sectional view taken along the line 10—10 of Figure 9;

Figure 11 is a sectional view taken along the line 11-11 of Figure 12;

Figure 12 is a fragmentary side view of a book bound by a binder formed from the blank of Figure 9; and

Figure 13 is a fragmentary transverse sectional view similar to Figure 11 and illustrating another embodiment of the present invention.

Reference may now be had more particularly to the binder of Figures 1 to 5. Figure 5 shows the complete binder 1 which includes a back 2 having a plurality of curled fingers 3 uniformly spaced apart, as indicated at 4. The fingers are of a width equal to the width of the spaces between the fingers. Figures 1 and 2 show a blank 15 from which the binder 1 is made. The blank is made of a comparatively thin sheet of spring steel cut or stamped to the shape illustrated in Figure 1 so that the fingers 3 are smooth and free of sharp corners and are rounded at their edges 5 and are also rounded at the finger ends 6 where the fingers extend from the back. In line with each finger 3 the back has a tab 8 stamped outwardly therefrom a short distance. The distance that the tab should extend need be only slightly in excess of the thickness of the material, or it may be even less than the thickness of the material, if desired. The tab 8 forms a V-shaped space 10 between the tab and the adjacent part of the back. When the individual fingers are curled the ends 11 of the fingers remote from the back 2 enter into the V space 10, as illustrated in Figure 3, thus firmly holding the ends of the fingers against collapse inward of the loop.

The blank 1 may be curled to the shape illustrated in Figure 4 and then forced into tubular formation to the shape illustrated in Figure 3 after the ends of the fingers 3 are inserted through aligned perforations 14 in a stack of pages or sheets 15 which may include covers 16-16 having similar perforations 14. If desired, however, the blank may be curled to the shape illustrated in Figure 3 before it has been inserted through the pages, and then the blank may be spread apart to move the fingers 3 away from the back 2 a sufficient distance to permit the fingers 3 to enter the perforations 14. The binder then is permitted to recur under its natural resiliency whereby it automatically resumes the shape illustrated in Figure 3 due to the inherent resiliency of the material. A suitable machine for inserting a preformed binder such as illustrated in Figure 3 into aligned perforations in a stack of sheets is illustrated in the patent to Christian B. Nelson and Isidore Spinner, No. 2,108,136, issued February 15, 1938. If the preformed binder is of a shape illustrated in Figure 4 then, when the fingers are forced in the perforations 14, the ends of the fingers 3 may be forced on the outside of the back a distance appreciably beyond the tabs 8 beyond the elastic limit of the material, and may then be withdrawn so that when they are guided to the inside of the back they will spring into the V slot 10 formed by the tab 8 with the back, thus firmly holding the curled spring fingers in the back.

Figures 6 and 7 illustrate individual finger rings similar to that of Figure 1, except that the rings are not joined together by a back. In this instance each ring of Figure 7 is formed from a spring steel blank 18 having a projection or tab 8 struck therefrom at one end in the same manner as illustrated in Figure 1. The spring steel blank 18 is perfectly flat and free of sharp corners, 70

the edges being rounded at the end 19, which is to be inserted in aligned perforations in a stack of pages. The blank 18 may be curled to the shape illustrated in Figure 7. Individual rings, 5 illustrated in Figure 7, may then be opened, without exceeding the elastic limit of the material, to permit positioning of a ring opposite a row of aligned perforations, in the same manner as is illustrated in Figure 3, and the rings then permitted to contract under their natural resiliency to reclose to the shape illustrated in Figure 7.

Reference may now be had more particularly to the binder blank illustrated in Figures 8, 9 and 10. This blank is made of thin spring steel and comprises a back 25 having spaced apart fingers 3 separated by spaces 4 of the same width as the fingers. The fingers are shaped the same as are the corresponding fingers of the blank of Figure 1. The back 25 has tabs 8' formed therein similar to the tabs 8 of Figure 1 but spaced slightly farther from the edge 26 of the back than in the case of the blank of Figure 1. The tabs 8' project from the surface of the back and are located each on the same center as a finger 3. Opposite each tab is a slot 27 of a width only very slightly greater than the width of a finger 3 so that upon curling of the finger the end of the finger fits snugly into the slot 27. Opposite each slot 27 the metal of the back is depressed, as indicated at 29, the depth of the depression 29 being slightly in excess of the thickness of the metal of the strip and preferably not to exceed twice the thickness of the metal. The free ends 30 of the fingers 3 are smooth and devoid of sharp corners, 33 and devoid of projections extending outwardly from a surface thereof, in order to facilitate insertion of the ends of the teeth into aligned perforations in a stack of pages, or withdrawal of the teeth from said perforations.

10 The binder of the blank of Figure 9 is curled either to the shape illustrated in Figure 4 or into a complete loop with the ends 30 of the fingers on the outside of the back 25. If the preformed binder is in the form of a complete loop with the ends 30 overlapping the outside of the back the binder is inserted into a machine such as shown in the patent to Nelson, et al., No. 2,108,136, issued February 15, 1938, the fingers are uncurled, without exceeding the elastic limit of the material, and then permitted to recur and pass through the aligned perforations 14 in the stack of pages 15 being bound. At that time the ends 30 of the fingers are forced into the slots 27 in the back until they come into abutment with the tabs 8'. The tabs 8' limit the extent of insertion of the fingers 30 in the loop. Thereafter, if a loop is subjected to axial compression, the finger 3 will not tend to slide in the loop of the binder. The narrow bridge 34 serves to hold the end of the finger against upward movement under its natural resiliency. The end of each curled finger lies in the depression 29 thus avoiding any protrusion or bulge on the outside of the binder at the place where the fingers extend through the back. The binder illustrated in Figure 11 may be opened to permit removal of pages therefrom by merely pulling the fingers outwardly from the slots 27 in the same manner as described in the above mentioned patent to Christian B. Nelson and Isidore Spinner.

When the book is in use the edges 36 of the slots 27 maintain the ends 30 of the fingers against movement in a direction lengthwise of the binder, thus maintaining a rigid structure.

Figure 13 illustrates, in fragmentary form, a

construction similar to Figure 11 except that the tabs 8' are somewhat longer, as in the case of Figure 1, so that the ends of the fingers 11 extend into the V slot 10 between the tab 8' and the back, as in Figure 3. Insofar as parts of this figure are the same as of Figure 11 the same reference numerals have been used.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

1. A binder comprising a back having a plurality of fingers extending therefrom and curled to form with the back closed loops with the fingers on the inside of the loops, the outer surface of the fingers being free of any concave curvature, and projecting tabs projecting inwardly from the back intermediate the width thereof and in alignment with fingers and constituting stops for limiting the curling of the fingers, the inner and outer surface of the curled fingers being smooth and devoid of outer projections to facilitate curling of the binder through material being bound.

2. A binder comprising a back having a plurality of fingers extending therefrom and curled to form with the back closed loops of more than 360°, and projecting tabs extending from the back in alignment with the fingers, the free end of each finger abutting against the tab aligned therewith for limiting the extent of overlap of the finger and the back, the free end of each finger being smooth at all its edges and surfaces and free of outward projections from any of its surfaces to facilitate insertion of said free ends into and withdrawal from aligned perforations in stacks of sheets to be bound.

3. A ring comprising a strip of spring material formed into a closed loop of more than 360°, one end of the strip being adapted for insertion through a slot and being curved along the same curvature as the rest of the loop to that very end of the strip, the opposite end of the strip having a slot therein through which said one end extends and having a projection spaced from the slot and forming an abutment against which said one end bears to limit the extent to which said one end can be inserted through the slot in the strip.
4. A ring comprising a strip of spring material formed into a closed loop of more than 360°, one end of the strip being adapted for insertion through a slot and being curved along the same curvature as the rest of the loop to that very end of the strip, the opposite end of the strip having a slot for receiving said one end of the strip and a projection adjacent to but spaced from said opposite end and extending from the periphery of the loop towards said opposite end and together with the adjacent part of the loop embracing said first mentioned end.
5. A ring comprising a strip of material formed into a closed loop of more than 360°, one end of the strip constituting a curved finger the inner and outer surfaces and the edges of which are smooth and devoid of outward projections to facilitate insertion of the ring through an opening in material to be secured by the ring and without injury to the material as the finger is inserted therein, said finger being curved along the same curvature as the rest of the loop to the very end of the finger, the opposite end of the strip having a projection adjacent to but spaced from said opposite end and adapted to receive the said one end of the strip to limit its movement in one direction along the inside of the loop.
